UNITED STATES PATENT OFFICE.

ARDEN J. MUMMERT, OF ST. LOUIS, MISSOURI.

PACKING-RING.

1,207,198.

Specification of Letters Patent.

Patented Dec. 5, 1916.

Application filed March 18, 1915. Serial No. 15,321.

To all whom it may concern:

Be it known that I, ARDEN J. MUMMERT, a citizen of the United States, residing at St. Louis, State of Missouri, have invented 5 certain new and useful Improvements in Packing-Rings, of which the following is a full, clear, and exact description, reference being had to the accompanying drawings, forming a part hereof.

10 My invention has relation to improvements in piston-head packing rings; and it consists in the novel features of construction more fully set forth in the specification and pointed out in the claims.

15 The present improvement is directed to packing rings of the resilient split band type which are deposited in annular grooves formed about the peripheries of pistons and piston valves in gas, steam and other motor-20 fluid driven types of engines, the special object of the present invention being to provide a packing ring of the character referred to which shall resist any tendency to leakage on the part of the motor fluid during 25 the driving stroke of the piston, and any tendency to leakage on the part of the oil film on the cylinder walls, past the piston and into the explosion chamber in gas engines, where the ring is employed on this 30 type of engine.

The advantages of the invention will be better apparent from a detailed description thereof in connection with the accompanying drawing in which—

35 Figure 1 is a longitudinal section through the cylinder of a gas engine with a piston in side elevation showing the application of my invention thereto; Fig. 2 is a plan view of the packing ring assembled; Fig. 40 3 is an edge view thereof; and Fig. 4 is an enlarged cross-section on the line 4—4 of Fig. 2.

45 Referring to the drawings, C represents the engine-cylinder, and P the piston, in the present example shown as equipped with a series of three of my improved rings. In the present embodiment of my invention, the ring comprises an outer resilient expanding or dilatable split band 1 provided with inwardly directed flanges α , α , along its opposite edges, whereby the band assumes the form of an annular channel, the open cavity of which receives an inner resilient contractile split band 2 whose edges are carefully

machined and loosely but snugly engage the 55 inner machined surfaces of the flanges α , α , of the outer band. As well understood in this art, the ring is deposited in an annular groove h of the piston P. In the present instance the inner band 2 being contractile 60 will hug the bottom of the groove; and the outer band 1 being expanding or dilatable, will hug the inner walls of the cylinder, the result being that more or less of an annular clearance d will be left between the outer 65 cylindrical face of the inner band 2, and the opposed or inner cylindrical face of the web portion of the outer channel band 1. The tendency of the inner band 2 to contract, and the outer band 1 to expand has 70 the following advantages: During the reciprocations of the piston P the tight fit between the cylinder walls and the outer band 1 prevents escape of any motor fluid during the driving action of said fluid or 75 driving stroke of the piston; and it prevents the escape of lubricating oil (which is usually in the form of a film on the inner cylinder walls) past the piston into the combustion or explosion chamber of the engine. 80 The tight joint formed by the contracting band 2 with the base of the groove h on the other hand prevents the escape of any oil which may find its way into the groove on the side facing the crank case, past the said 85 band, and thus escape of oil into the explosion chamber is impossible. This joint of course likewise prevents the escape of the motor fluid past the piston during the driving stroke of the latter, the "driving" 90 stroke being the stroke the piston makes under the driving action of the fluid or gases.

I do not wish of course to limit myself to the precise details here shown as they may 95 in a measure be departed from without affecting the nature or spirit of my invention.

Neither do I wish to be restricted to any specific number of bands which compose 100 the packing ring. As shown in the drawings and pointed out in the description, the members 1, 2, normally tend to draw away from each other along a plane transverse or at right angles to the axis of the ring, that 105 is to say in a "radial" plane. It is due to this drawing away of the bands from one another which gives rise to the clearance d .

Some clearance of course would always be desirable to permit the bands to perform their proper function.

Having thus described my invention what 5 I claim is:

1. A packing ring comprising an inner band and an outer band enveloping the inner band, the adjacent faces of the respective bands tending to separate one from the 10 other under normal operating conditions of the ring.
2. A packing ring comprising an inner contracting split member, and an outer expanding split member, one of the members 15 being grooved or channeled to receive the other member.
3. A packing ring comprising an outer resilient expanding split band, and an inner resilient contracting split band, one of the 20 bands being provided with flanges overlapping the other band.
4. A packing ring comprising an outer resilient expanding split channel band, and an inner resilient contracting split band embraced by said outer band and lying within 25 the channel thereof.
5. A packing ring comprising an outer resilient expanding split band provided with inwardly directed flanges along its opposite edges, and an inner resilient contracting split band confined between the flanges of the outer band.
6. A packing ring comprising an outer

resilient expanding split band provided with inwardly directed flanges along its opposite edges, and an inner resilient contracting split band confined between and engaging with its opposite edges the adjacent inner surfaces of the flanges of the outer band.

7. In a piston-head packing ring, an annular resilient expanding split channel band adapted to be interposed between the piston and cylinder, the channel of the band facing the axis of the ring, and an annular contractile band operating in the channel of the first mentioned band.

8. In a packing ring, a pair of annular resilient members disposed in concentric relation to one another and operating to draw 50 radially away from each other, one member lying within a groove of the opposite member.

9. In a packing ring, a pair of annular resilient bands mounted one within the 55 other, and operating to draw away from each other, in a plane transverse to the axis of the ring, the outer band being provided with a groove or channel in which the inner band permanently lies.

In testimony whereof I affix my signature, in presence of two witnesses.

ARDEN J. MUMMERT.
